PREPARATION OF FOUNDATION COLUMNS

Edward A. Smith, Chatham, N. J., assignor to
Raymond Concrete Pile Company, New York,
N. Y., a corporation of New Jersey

Application October 5, 1933, Serial No. 692,255

5 Claims. (Cl. 61—57.)

This invention pertains to improvements in method and apparatus for forming concrete columns as disclosed in Hart and Schroeder Patent No. 1,931,845.

In that disclosure the hole in the ground is sunk by means of an annular drill or core cutter which forms the lower section of the casing for the mold, the upper casing section following the lower section down into the hole as the drilling proceeds.

The present invention contemplates keeping the upper casing section out of the hole until the lower section comprising the drill has reached the desired depth, then lowering the upper section into watertight relationship with the lower section so that the hole may be pumped out and inspected, after which the hole is filled with concrete to form the column, the casing sections being either left in the hole to become part of the column, or withdrawn during or after the pouring of the concrete.

Further and other objects and advantages will be apparent from the specification and claims, and from the accompanying drawings which illustrate what is now considered the preferred embodiment of the invention.

Fig. 1 shows the annular drill in position after drilling has been finished and before removal of the driving head and shaft.

Fig. 2 is the same as Fig. 1 after the driving head has been removed and the upper section of the casing has been lowered into position on the lower section, the conical guide ring being still attached to the bottom of the upper section.

Fig. 3 is an enlarged detail showing clamps for locking upper and lower casing sections together, and the hoisting cables.

Fig. 4 is a view on line 4—4 of Fig. 3.

Fig. 5 illustrates a modification in which the casing is of reduced diameter with reference to the cutter, the casing and cutter being partially withdrawn.

Fig. 6 is an enlarged sectional view of Fig. 5.

In the drawings (Fig. 1) 10 designates a drill barrel of the type disclosed in the above mentioned Hart et al application. 12 is the drive head and 14 is the hollow drive shaft. The drive head has ears 16, adapted for automatic engagement or disengagement with lugs 18 welded or riveted to a steel ring 20 integral with the drill barrel. The outer shell of the drill is extended upwardly above ring 20 to form a skirt 22 with its upper edge beveled as at 24 and having an internal circumferential ring 26 having its upper edge beveled as at 28 to form a conical seat.

Fig. 1 shows the above mechanism at the completion of the drilling operation, with the hole and drill barrel full of mud, or mud-laden fluid (not shown) which prevents caving of the unlined hole above the drill, the mud usually consisting of earth loosened by the drill and water fed to the drill. Under certain circumstances mud-laden fluid is even fed to the drill to act as a cutting agent. The cutting edge of the drill has penetrated into rock 30, and the drive head and drive shaft are in operative position.

Fig. 2 shows the layout after head 12 and shaft 14 have been removed and the upper section of casing 32 has been lowered through the mud. 15 The lower end of casing section 32 is provided with a detachable sectional conical guide ring 34 secured by bolts 36 to a steel ring 38 integral with the upper casing. The lower outer surface of ring 38 is conical as at 40 to form a continuation 20 of the outer conical surface of guide ring 34. Set into the outer surface of ring 38, above its conical portion, is a ring 42 of rubber or other resilient packing. It will be observed that first ring 34, and then ring 38, engage the upper end of skirt 22 25 to align casing section 32 with the drill barrel, the conical portion 40 of ring 38 being seated on the conical seat 28 of ring 26 and the beveled edge 24 of the skirt being imbedded in packing ring 42, thus providing a fluid tight joint between the drill barrel and casing 32.

The mud-laden fluid is then pumped from the casing and drill barrel, after which a man is lowered into the casing to loosen bolts 36 so that guide ring 34 may be removed. Then any solids 35 which have settled into the drill barrel are removed and the bottom of the hole (usually rock) is cleaned off for receiving the concrete. The hole may then be filled with concrete to form the column, leaving casing and drill barrel in place, 40 or, if desired, the casing and barrel may be removed.

If removal of barrel and casing is desired, they are first clamped together as shown in Fig. 3. The upper surface of ring 38 is provided with 45 sockets or a groove 44 (Figs. 3 and 4) to accommodate lugs 46 of upper clamp jaws 48 to prevent them from slipping out of place when the hoisting strain is applied. The lower clamp jaws 50 are heads of bolts 52 and have inclined lips 54 50 adapted to engage the beveled lower edge of ring 20. As many clamping bolts as may be needed are applied as in Figs. 3 and 4 and are clamped tight by means of nuts 56. Hoisting cables 58 are attached to upwardly extending ears 60 in- 55

tegral with upper jaws 48. Then as the concrete is poured or after the pouring is completed, casing and drill barrel are withdrawn from the hole, in well known manner.

5 Although the drill barrel must always be the full diameter of the hole, the casing above the drill barrel may, under certain conditions, be of less diameter (Figs. 5 and 6). This is important from the standpoint of economy, because a single 10 casing may be used with several sizes of drills. To connect the reduced-diameter casing to a core barrel an adapter may be used, having a short full-diameter section 62 with a conical roof 64, to which is bolted the bottom section 66 of the 15 reduced casing, which need only be of sufficient diameter to permit passage of a man and possibly a pump.

After the drill barrel and casing 66 are pumped out, the mud remains undisturbed above roof 64 20 and around the outside of casing 66, thereby preventing caving of the walls of the hole.

When the reduced-diameter casing is used, the hoisting cables 68 may be attached to ribs 70 on roof 64, to permit withdrawal of the drill and 25 casing progressively as the concrete 72 is poured.

It is to be understood that the invention is not limited to the specific embodiment herein illustrated and described, but may be used in other ways without departure from its spirit as defined 30 by the following claims.

I claim:

1. The method of forming a foundation column, which comprises sinking a drill barrel into the ground, lowering an annular casing into engagement with said barrel, removing the contents of 35

said barrel and casing, and filling said barrel and casing with concrete to form the column.

2. The method of forming a foundation column, which comprises sinking a drill barrel into the ground, lowering an annular casing into engagement with said barrel, removing the contents of said barrel and casing, locking said barrel to said casing, filling said barrel and casing with concrete, and withdrawing said barrel and casing together. 10

3. The method of forming a foundation column, which comprises sinking a drill barrel into the ground, lowering an annular casing into engagement with said barrel, removing the contents of said barrel and casing, locking said barrel to 15 said casing, and filling said barrel and casing with concrete to form the column.

4. The method of forming a foundation column, which comprises sinking a drill barrel into the ground, lowering an annular casing into engagement with said barrel, removing the contents of said barrel and casing, locking said barrel to said casing, filling said barrel and casing with concrete to form the column, and withdrawing 20 said barrel and casing as the filling progresses. 25

5. The method of forming a foundation column, which comprises sinking an annular drill into the ground, lowering an annular casing into engagement with said drill, sealing the lower end of said casing to the drill, removing the contents of said drill and casing, and filling said drill and casing with concrete to form the column. 30

EDWARD A. SMITH. 35
